UNITED STATES PATENT OFFICE.

WILLIAM S. DAVIS, OF SACRAMENTO, CALIFORNIA, ASSIGNOR OF ONE-HALF TO
CHARLES E. EMERSON, OF SUSANVILLE, CALIFORNIA.

WATER-HEATER.

1,260,757.

Specification of Letters Patent. Patented Mar. 26, 1918.

Application filed June 11, 1917. Serial No. 174,157.

To all whom it may concern:

Be it known that I, WILLIAM S. DAVIS, a citizen of the United States, residing at Sacramento, in the county of Sacramento and 5 State of California, have invented certain new and useful Improvements in Water-Heaters, of which the following is a specification, reference being had to the accompanying drawings.

10 This invention relates to certain improvements in water heaters and it is an object of the invention to provide a device of this general character having novel and improved means whereby water may be heated 15 for domestic or other purposes or generated into steam.

It is also an object of the invention to provide a novel improved device of this general character comprising two communicating 20 water containers adapted to coact for the production of hot water and whereby one of said containers is adapted to be separated from the second container when it is desired to generate steam.

25 The invention consists in the details of construction and in the combination and arrangement of the several parts of my improved water heater whereby certain important advantages are attained and the device is rendered simpler, less expensive and otherwise more convenient and advantageous for use, all as will be hereinafter more fully 30 set forth.

The novel features of the invention will 35 hereinafter be definitely claimed.

In order that my invention may be the better understood, I will now proceed to describe the same with reference to the accompanying drawings, wherein

40 Figure 1 is a diagrammatic view with parts in elevation and parts in section of a water heater constructed in accordance with an embodiment of my invention; and

Fig. 2 is a sectional view taken substantially on the line 2-2 of Fig. 1.

As disclosed in the accompanying drawings 45 1 denotes a pedestal or standard for supporting the vertically disposed hollow member 2 preferably cylindrical in form and 50 having its opposite ends closed. At predetermined points intermediate its length the member 2 is intersected by the longitudinally spaced partitions 3 and 4 affording a chamber C therebetween. In communication 55 with the chamber C through the upper par-

tition 3 is a flue F positioned at substantially the axial center of the container 2 and extending exteriorly thereof through the top of said container. In communication with the chamber C through the lower partition 4 60 is a cylindrical hood or flue 5 extending entirely between the lower partition 4 and the lower end of the container 2.

Positioned within the chamber C is a receptacle R of a major diameter less than the 65 diameter of the chamber C and of a length less than the chamber C. It is also preferred that the receptacle R be gradually tapered downwardly. The construction of the receptacle R is such as to readily permit 70 the products of combustion to readily pass therearound for exit through the flue F.

Connecting the upper portion of the receptacle R and the lower portion of the compartment within the container 2 above the 75 partition 3 is the pipe 6 having interposed therein the controlling valve 7. Also in communication with the lower portion of the container 2 above the partition 3 and with the lower portion of the receptacle R, is a 80 second pipe 8 having interposed therein a controlling valve 9.

In communication with the upper and lower portions of the receptacle R are the pipes 10 and 11 respectively and each of 85 which has interposed therein a controlling valve 12. The lower pipe 11 is also provided with the cock 14. Interposed between and in communication with the pipes 10 and 11 is a gage glass 15. The outer ends of the 90 pipes 10 and 11 are in communication with a lead pipe 16 and the portion 16a of said pipe intermediate the pipes 10 and 11 serves as a bleeder.

Arranged within and extending longitudinally of the hood or flue 5 is a heating coil 17 having its lower end extending as indicated at 18 exteriorly of the container 2 and terminating in the cock 19. In communication with the extension 18 of the coil 17 at a point intermediate the container 2 and the hood or flue 5 is the pipe 20 which extends upwardly and has communication with the upper compartment of the container 2 through the upper partition 3. It is preferred that the pipe 20 be wholly confined 100 within the container 2.

The upper portion of the coil 17 is continued in the pipe 21 which extends upwardly through the chamber C and through 110

the flue F preferably at the axial center thereof and is in communication with the upper compartment of the container 2 through the wall of the flue F at a point in close proximity to the top of the container.

Also in communication with the upper compartment of the container 2 is the pipe 22 terminating in close proximity to the upper partition 3 and which is in communication 10 with a suitable source of water supply. Interposed in the pipe 22 is the controlling valve 23. The upper compartment of the container 2 has also in communication therewith, at a point adjacent its top, the pipe 24 through which is adapted to be drawn the heated water within the upper compartment of the container 2 and interposed in 15 said pipe 24 is the controlling valve 25.

Supported by the lower end of the container 2 and in communication with the hood or flue 5 is a heating member M including a plurality of liquid fuel burners B each of which has separate communication through the medium of the pipes 26 with a 20 common source of fuel supply, as indicated by the pipe 27. Interposed in each of the pipes 26 is a glass 28 to afford visual access within said pipes 26 to observe the flow of fuel therethrough. Interposed in one of the 25 pipes 26 is a needle valve 29 automatically operated by the thermostat T suitably mounted upon the pipe 24 so that when the temperature of the water passing through said pipe 24 has reached a predetermined 30 degree the thermostat T will operate to automatically close the valve 29 so that one of the burners B can be regulated in order to maintain the heated water in substantially an even temperature. The second pipe has 35 interposed therein the needle valve 30 adapted to be manually operated to control the flow of the fuel through said second pipe 26. The heating member M, as herein disclosed, is more particularly described and 40 claimed in my copending application executed on even date herewith. It is, therefore, to be understood that in my present invention any proper heating means may be 45 employed which will operate with convenience and facility.

When it is desired to use my improved heater solely for the purpose of heating water the valve 23 and the pipe 22 are 50 opened and are permitted to remain open until the upper compartment of the container 2, the coil 3, the pipes 20 and 21 together with the coils 17 and the receptacle R are filled. It is also to be understood that in the water heating operation the valves 7 55 and 9 in the pipes 6 and 8 respectively are opened. When it is desired to employ my improved device solely for the purpose of generating steam the valves 7 and 9 are closed and the valves 12 in the pipes 10 and 60 65 11 opened. The cock 14 is also opened until

the water line within the receptacle R is at a predetermined point below the communication between the pipe 6 and the receptacle 5 to create the necessary steam space. It will also be self-evident that the water line 70 or level within the receptacle R can be readily determined by the gage glass 15. The steam as generated within the receptacle R may be delivered by the lead pipe 16 as desired and said steam may be employed as 75 preferred.

From the foregoing description, it is thought to be obvious that a water heater constructed in accordance with my invention is of an extremely simple and comparatively inexpensive nature and is particularly well adapted for use by reason of the convenience and facility with which it may be assembled, and it will also be obvious that my invention is susceptible of some change 85 and modification without material departure from the principles and spirit thereof and for this reason I do not wish to be understood as limiting myself to the precise arrangement and formation of the several 90 parts herein shown in carrying out my invention in practice, except as hereinafter claimed.

I claim:

1. A water heater comprising an elongated container, two longitudinally spaced partitions intersecting said container and affording end compartments and an intermediate chamber, a flue in communication with the chamber through one of the partitions and extending exteriorly of the container through an end thereof, a water inlet pipe in communication with the compartment through which the flue is directed, a closed receptacle positioned within the 100 chamber, a valve controlled connection between the receptacle and the water compartment, a valve controlled discharge pipe in communication with the water compartment, a valve controlled pipe in communication with the receptacle and terminating exteriorly of the container and a heating medium in communication with the second end compartment. 105

2. A water heater comprising an elongated container, two longitudinally spaced partitions intersecting said container and affording end compartments and an intermediate chamber, a flue in communication with the chamber through one of the partitions and extending exteriorly of the container through an end thereof, a water inlet pipe in communication with the compartment through which the flue is directed, a closed receptacle positioned within the 120 chamber, a valve controlled connection between the receptacle and the water compartment, a valve controlled discharge pipe in communication with the water compartment and a valve controlled pipe in communication 125 with the receptacle and terminating exteriorly of the container and a heating medium in communication with the second end compartment.

- tion with the receptacle and terminating exteriorly of the container, a coil positioned within the second end compartment and having one end in communication with the water compartment, the opposite end of the coil being extended through the chamber and through the flue and communicating with the water compartment adjacent the outer end thereof and means for heating the coil.
3. A water heater comprising an elongated container, two longitudinally spaced partitions intersecting said container and affording end compartments and an intermediate chamber, a flue in communication with the chamber through one of the partitions and extending exteriorly of the container through an end thereof, a water inlet pipe in communication with the compartment through which the flue is directed, a closed receptacle positioned within the chamber, a valve controlled connection between the receptacle and the water compartment, a valve controlled discharge pipe in communication with the water compartment and a valve controlled pipe in communication with the receptacle and terminating exteriorly of the container, a coil positioned within the second end compartment and having one end in communication with the water compartment, the opposite end of the coil being extended through the chamber and through the flue and communicating with the water compartment adjacent the outer end thereof and means for heating the coil, the lower portion of the coil being provided with a valve controlled extension extending exteriorly of the container.
4. A water heater comprising a container, a partition intersecting said container and affording a water compartment, a water inlet pipe in communication with said water compartment, a closed receptacle positioned within the container below the water compartment, a heating means arranged below the receptacle, a valve controlled pipe in communication with the lower portion of the water compartment and the upper portion of the receptacle, a second valve controlled pipe in communication with the lower portion of the water compartment and the lower portion of the receptacle, a valve controlled discharge pipe in communication with the upper portion of the water compartment, valve controlled pipes in communication with the upper and lower portions of the receptacle and extending exteriorly of the container, a lead pipe in communication with said lastnamed pipes, and a gage glass interposed between and in communication with the extended portion of the last named pipes in communication with the receptacle.
5. A water heater comprising a container, a partition intersecting said container and affording a water compartment, a water inlet pipe in communication with said water compartment, a closed receptacle positioned within the container below the water compartment, a heating means arranged below the receptacle, a valve controlled pipe in communication with the lower portion of the water compartment and the upper portion of the receptacle, a second valve controlled pipe in communication with the lower portion of the water compartment and the lower portion of the receptacle, a valve controlled discharge pipe in communication with the upper portion of the water compartment, valve controlled pipes in communication with the upper and lower portions of the receptacle and extending exteriorly of the container, a lead pipe in communication with said lastnamed pipes, and a gage glass interposed between and in communication with the extended portion of the last named pipes in communication with the receptacle.
6. A water heater comprising a container, a partition intersecting said container and affording a water compartment, a water inlet pipe in communication with said water compartment, a closed receptacle positioned within the container below the water compartment, a heating means arranged below the receptacle, a valve controlled pipe in communication with the lower portion of the water compartment and the upper portion of the receptacle, a second valve controlled pipe in communication with the lower portion of the water compartment and the lower portion of the receptacle, a valve controlled discharge pipe in communication with the upper portion of the water compartment, valve controlled pipes in communication with the upper and lower portions of the receptacle and extending exteriorly of the container, a lead pipe in communication with said lastnamed pipes, and a cock interposed in the lowermost of the lastnamed pipes in communication with the receptacle.

In testimony whereof I hereunto affix my **110**
signature in the presence of two witnesses.

WILLIAM S. DAVIS.
